ARC LAMP

William R. Gruber, New York, N. Y., assignor to
Health Ray Laboratories, Inc., "Health" Ray Mfg. Co. Inc., New York, N. Y.,
a Corporation of New York

Application February 6, 1931. Serial No. 513,875

4 Claims. (Cl. 176—103)

This invention relates to illuminating devices in general and more specifically to the type adapted for use in connection with photography.

One of the objects of this invention is to provide a simply constructed, relatively inexpensive, compact, easily portable, safely and conveniently operable device of this kind, which is designed to create light of sufficient intensity and brilliancy, without the production of smoke or noise to enable making a photographic exposure without adversely affecting the subject to be pictured, due to nervous shock inflicted by the suddenness with which the light develops.

Another object of the present invention is to provide a relatively small device of this kind which may be readily still further reduced in size for the purpose of shipment or other transportation, in that its support may be secured within the body of the device when not in use.

Another object of this invention is to so construct the device as to form a relatively small casing divided into distinct, physically separated resistance receiving and electrode housing compartments, the latter provided with adjustable reflector means adapted to form walls or sides for said electrode compartment.

The foregoing and still further objects of this invention will become more fully apparent from the following description and the accompanying drawings, forming part of my disclosure, and illustrating a few of the at present preferred constructions, but by no means intended to limit my invention to the actual showing, and in which,

Fig. 1 is a perspective view of a single arc lamp of my construction supported by a stand.

Fig. 2 is a perspective view of my device in its collapsed form.

Fig. 3 is a vertical cross-sectional view through my device shown in Fig. 1.

Fig. 4 is a horizontal cross sectional view taken on line 4—4 of Fig. 3.

Fig. 5 is a perspective view of my double arc lamp.

Fig. 6 is a cross sectional view taken on line 6—6 of Fig. 5, and

Fig. 7 is a top view, partially in cross section, of a quadruple arc lamp of my construction.

Referring to the illustration in Figs. 1, 2, 3 and 4, numeral 10 denotes a casing, preferably made of light material, as for instance aluminum, and comprising a resistance receiving compartment 11 and an electrode housing compartment 12. The former is provided with air ventilation means, indicated at 13, which serves for effecting cool-

ing of a resistance element 14, mounted in this compartment, preferably upon a dielectric core 15.

The electrode compartment 12 forms an extension of the resistance compartment and is divided therefrom by a partition 16 secured to bottom 17 and top 18 of the casing. Secured to bottom 17 and top 18 are dielectric electrode supports 19 and 20 resting against insulation sheets 21 which separates them from the casing material. Each of the supports is provided with a hollow channel 22 for accommodating wiring and binding posts.

The lower electrode support 19 has a conductive plate 23 at its top, which is perforated at its center and held in place by screws 24, to one of which is attached one lead of the double electric conduit 25, entering through bottom 17 of the casing and lower insulation sheet 21 into channel 22 of lower electrode support 19. The other lead of conduit 25 is attached to screw 26 mounted in offset extension 27 of the electrode support. To the same screw 26 is secured the lower end of resistance element 14 in the form of a clamp 28, which serves also as support for core 15.

The upper electrode support 20 is provided with an aperture 29 for receiving the upper electrode 30 and is equipped with a conductive plate 31 held in place by screw 32 and terminating in a spring extension 33 projecting into aperture 29 and adapted to bear against electrode 30. Plate 31 is perforated to accommodate the electrode which is manually adjustable in aperture 29. An electric conduit 34 is attached with one end to screw 32, while its other end makes contact, by way of screw 35 in offset extension 36 of the upper support, with clamp 37, forming the upper terminal of resistance element 14 and upper suspension for core 15.

In the lower electrode support 19 a manipulating device for the lower electrode 38 is illustrated and consists of a conductive rod 39 slidably mounted in aperture 40, provided in lower support 19, and extending through the perforated plate 23. Its upper end is equipped with an electrode holding clip 41, while at its lower end a dielectric handle or knob 42 is shown, which serves for lifting the rod, and thereby the lower electrode, in the direction towards the upper electrode, for the purpose of causing the electrodes to contact preparatory to forming an electric arc between them. Due to its weight the device normally rests with the bottom of the clip against plate 23 at the upper face of the support, and since it is slidably mounted in the latter, it reverts to this normal

position after having been temporarily elevated for the aforesaid purpose.

Partition 16 dividing the two compartments serves as a stationary light reflecting surface for the arc light produced between the electrodes.

Hinged at the bottom and top plates of the casing and adjacent to partition 16 are side members 43, which, when swung out as shown in Figs. 1 and 4, serve with their inner surfaces as side reflectors.

10 When in inoperative position, as shown in Fig. 2, the side members form side closures or side walls for the electrode compartment.

Electric conductor 25 is preferably equipped with a hand switch 44 (see Fig. 1) for controlling 15 the current to be admitted to the device.

At the portion of the casing forming the bottom plate of the resistance compartment is provided bushing 45 adapted to receive the upper end of a combination handle and stand 46. The lat-

20 ter serves as support for the upper structure of my device, when in use, and may be secured within the casing when the device is to be shipped or carried, as shown in Fig. 2 and indicated in broken lines in Fig. 3. The combination handle and

25 stand preferably consists of a base 47 from which projects a standard comprising an inner bolt 48 and a handle member 49 made of dielectric material or wood. Bolt 48 is threaded at its upper end and adapted to engage the threaded interior 30 of bushing 45 from either without or within the casing.

In Figs. 5 and 6 is illustrated a device similar to that explained above, with the exception that instead of a single pair, two pairs of electrodes 35 are arranged in the electrode compartment, which of course is somewhat larger in size. The lower electrodes 50 and the lower ends 51 of resistances 52 are bridged, as seen at 53, while the upper ends 54 of the resistances are separately connected with upper electrodes 55. The double electrode provision serves for intensifying the light effects, when a single pair of electrodes would be insufficient. When commencing to produce arc lights in the double electrode device 40 it is necessary to first elevate one of the lower electrodes until an arc is produced between it and its corresponding upper mate, and then repeat the operation with the second electrode, so as to avoid excessive load in the line supplying current to 50 the device.

The construction of the resistance element 52 is somewhat different from that previously explained, since the resistance cores or supports are omitted. Also the end clamps are eliminated, 55 since this type of resistance is self supporting.

In Fig. 7 a somewhat modified form of my device is illustrated in which four pairs of electrodes are provided. Such construction is designed for enabling the illumination of a larger area from all sides, if desired, or from one or more angles as the requirement may be. It consists of four distinct and individually useable electrode compartments 56, 57, 58 and 59, grouped about a central resistance compartment 60, in which a plurality of resistances (not shown) are individually coupled with the upper electrodes (not shown) and disposed above lower electrodes 61, shown in section. The structural arrangement of this modified form is otherwise identical with the previously described figures, with the exception that the four dividing walls 62 are stationary.

My device is capable of still further modifications, and while I have described only those shown in the drawings, it is self-understood that 75 changes and improvements may be incorporated,

and I therefore reserve for myself the right to make such changes and improvements without departing from the broad scope of my idea covered by the appended claims.

I claim:—

1. In an arc lamp including resistance and electrode compartments, having common tops and bottoms, upper and lower dielectric electrode supports extending from said resistance compartment into said electrode compartment, said upper support having an electrode holder adapted to fixedly retain an upper electrode in substantially vertical position, said lower electrode support provided with a fixed electrode contact, a lower electrode holder operatively associated with said contact and adapted to engage and to hold the lower electrode in substantially vertical position and in alignment with an upper electrode, said lower electrode holder adapted to normally rest against said contact due to its own weight and the weight of the electrode, and capable of being temporarily elevated in order to bring the lower electrode into momentary contact with the upper electrode. 80

2. In an arc lamp, a pair of dielectric electrode supports, composed of upper and lower members, spaced from each other, and adapted to receive and retain electrodes in a substantially vertical alignment, the upper member having means for adjustably holding an upper electrode in fixed 105 position, the lower member provided with a rest-contact and guide means for an electrode holder, a lower electrode holder operatively mounted in said guide means, projecting through and normally reposing upon said rest-contact, and adapted to be temporarily elevated above said rest-contact for the purpose of causing a momentary abutment between the electrodes of the two supports. 95

3. In an arc lamp, the combination with a resistance and an electrode housing, of a pair of dielectric electrode supports, forming upper and lower member separated from each other, the upper member provided with a resilient electrode holder adapted to adjustably retain the upper 120 electrode in substantially vertical position, the lower member provided with guide means and a contact arrangement, a lower electrode holder operatively mounted in said guide means and comprising a stem, an electrode receiver at the 125 upper end of the stem, and a dielectric handle at its lower end, said electrode receiver adapted to normally rest upon said contact arrangement, due to the combined weight of the lower electrode holder and its electrode, said stem adapted to 130 always retain contact with said contact arrangement, said lower electrode holder capable of being temporarily elevated for the purpose of causing momentary contact between upper and lower electrodes. 135

4. In an arc lamp, the combination with a combined resistance and electrode housing, of a pair of dielectric electrode supports spaced from each other and forming upper and lower members, disposed, respectively, near the top 140 and bottom of the housing, a resilient upper electrode holder secured to the upper member and adapted to adjustably retain an upper electrode in substantially vertical position, the lower electrode support member provided with a guide 145 aperture and a contact plate, having a perforation registering with said aperture, secured to the upper face of said member, a lower electrode holder operatively associated with said guide aperture and said plate, and comprising a stem 150

guided in said aperture, a lower electrode receiver secured to the upper end of the stem, and a dielectric knob at the lower end of said stem, the lower electrode holder adapted to be normally positioned so that its electrode receiver rests upon said contact plate, due to the combined weight of the holder and its electrode, the holder being further adapted to be elevated by lifting it at the knob, for the purpose of causing the electrodes to temporarily contact with each other, and to revert to its normal position when released, said stem permanently contacting with said plate while the holder is either at rest or 80 while being operated.
